Inventor:
Abraham Eisenberg.

Att'y.

UNITED STATES PATENT OFFICE

ABRAHAM EISENBERG, OF NEW YORK, N. Y.

ORNAMENTAL AND EDUCATIONAL DEVICE

Application filed July 25, 1928. Serial No. 295,278.

My invention relates to a new and improved ornamental and educational device and more particularly has reference to a plaque or other like work of art which is so constructed as to contain a booklet relating to the subject matter of the plaque.

It is accordingly an object of my invention to provide a device presenting an ornamental and instructive design in the form of a plaque, 10 painting, or the like, which device is adapted to contain a booklet having a bearing upon and of particular interest to such design.

A further object of my invention resides in the provision of a device of the character set forth which may be either suspended upon 15 a wall or set up upon a desk or table in a manner similar to an easel for ornamental and/or instructive purposes.

A still further and more specific object of 20 my invention resides in the provision of an ornamental device which on its front portion presents a reproduction of a work or works of art and on its rear portion is provided with a compartment or pocket for 25 movably retaining a booklet elaborating upon the subject or subjects of the front portion of the device.

Still another object of my invention resides 30 in the provision of a device of the character set forth which is simple in construction and inexpensive in manufacture.

Briefly described, my invention consists in forming, as by stamping or otherwise, upon 35 sheet material, preferably metal, an ornamental design or a reproduction of a work of art; providing said sheet material with a backing, also preferably of metal, in which is formed a compartment having means for suspending a booklet or pamphlet therein; and 40 providing the compartment with a hinged closure or cover, which closure or cover forms a support for the device when it is to be set up in easel fashion. At a mid-point in the upper portion of the back is provided an element for suspending the device as by hanging 45 on a wall, this hanging means cooperating with a catch in the compartment closure for bracing the latter when it is desired to stand the device on a table or desk instead 50 of suspending it on a wall. The back por-

tion of the device is also provided with a pivoted leaf or button for retaining the compartment cover in closed position when not employed as a back rest and for holding the pages of the booklet together when the cover is opened to support the device as an easel.

In the preferred embodiment of my invention, the ornamental and instructive subject on the front face of the device comprises a metallic plaque on which is reproduced in relief in any known manner, as by an appropriate stamping process, a plurality of medallions each portraying the profile of a President of the United States, his name, and period of incumbency. The medallions are 60 preferably arranged successively in accordance with the terms of office of the men they portray with the Washington medallion occupying a prominent position at the upper 65 central portion of the plaque. Suitable ornamentation is provided on the plaque in addition to the medallions in order to further beautify the entire front face of the device. In this preferred embodiment of the invention, the compartment in the rear of the plaque 70 retains a booklet containing a brief biography of each of the Presidents portrayed on the plaque.

It will of course be understood that my invention is not limited to the modification above set forth as any group of men or objects may form the subject matter of the plaque and its associated booklet. Likewise the ornamental front face of the device need not be a metallic plaque but may be formed of other materials and may be a photograph, print, painting, or the like. The ornamental portion of the device may in fact be a reproduction of any work of art or subject of interest which is described or elaborated upon in the accompanying booklet the essence of the invention residing in the association with an ornamental and/or instructive device of a booklet descriptive thereof.

For a more detailed understanding of my invention, reference will be had to the accompanying drawing showing preferred forms of my improved device but it is to be expressly understood that the invention, as

65

70

75

80

85

90

95

100

defined in the appended claims, is by no means limited thereto.

In the drawing, Fig. 1 is a view of the front face of the device;

5 Fig. 2 is a view of the opposite side of the device showing the booklet compartment cover in closed position;

10 Fig. 3 is a section through the center of the device showing the same set up in the manner of an easel; and

15 Fig. 4 is a sectional view of a modified construction.

In the drawing like reference characters refer to similar parts in the different views.

15 The numeral 10 indicates the front face of the device which, as stated, in the preferred embodiment of the invention comprises a metallic plaque on which are stamped the medallions 11 in definite arrangement and the 20 additional ornamentation 12 and 13. When thus formed in relief upon appropriate metal, the reproduction is especially artistic although an ornamental design may be applied to the front portion 10 in any other 25 manner. A backing 14 is provided for the plaque although this is not essential.

30 The rear portion of the device comprises in part a sheet of metal 15, the center of which is cut out as shown, and suitably fixed to the plaque 10 and the backing 14 as by a bead 16 or by soldering. A cover or closure 17, hinged at 18, completes the rear face of the device. By reference to Fig. 3 it will be seen that the sheet metal 15 inclines away 35 from the backing 14 to form under the cover 17 a compartment 19 adapted to contain the booklet 20 relating to the subject matter of the plaque. The booklet 20 is preferably suspended on hair pin wire 21 extending 40 across the upper portion of the compartment below the hinge 18 and looped through the hinges 18 as clearly shown in Fig. 2. Thus suspended, the booklet may be easily removed from the compartment.

45 A wire loop 22, hinged at 23, when in the upper position of Fig. 2 forms a convenient means for suspending the device on a wall. In the lower position shown in Fig. 3, the loop 22 cooperates with a cup-shaped member 24, either soldered to or stamped out of the cover 17, to brace the latter whereby the cover may form a back rest or support for the device should it be desired to set the same up as an easel upon a desk or table.

50 A retaining member in the form of a leaf or button 25, pivoted for rotation at 26 on the sheet 15 adjacent the lower edge of the cover 17, serves to hold the latter in closed position and when the cover is employed as 55 a back rest as shown in Fig. 3, the member 25 retains the booklet within compartment 19 and holds the pages thereof from falling toward the open cover 17.

60 In Fig. 4 I have shown a modification of the device which is still simpler in construc-

tion than the one above described and which comprises but two major parts. In this view the plaque and compartment cover are the same as in Figs. 1, 2, and 3. However, the plate 14 is omitted and the backing of sheet 65 metal 15' is made coextensive in size with the front face or plaque. The sheet 15', instead of having its central portion cut out as in the above described modification, has its central portion bent inwardly toward the 70 plaque as shown at 15'' to thereby form a compartment 19' in which the booklet 20' is suspended on the hair pin wire 21'. As above, this wire is here too looped through the hinges of the cover. The construction 75 as illustrated in Fig. 4 effects a considerable saving in material and cost of manufacture.

80 From the foregoing it will be seen that I have provided an ornamental and educational device comprising a plaque or the like and means for associating therewith a booklet relating thereto and which device may be employed either as a hanging or easel type of ornament and which is simple in construction and inexpensive in manufacture.

85 While I have described with particularity preferred forms of my invention, it will be apparent that various changes and modifications may be made therein without departing from the spirit and scope of the invention as defined in the appended claims.

90 Having described my invention what I claim as new and desire to secure by Letters Patent is:

100 1. A device of the character described comprising an ornamental front portion, a rear portion having a compartment, a hinged closure for said compartment forming a back rest for the device when in open position, and a wire extending across the upper portion of 105 said compartment for suspending a booklet therein.

110 2. A device of the character described comprising an ornamental front portion, a rear portion having a compartment adapted to contain a booklet, a hinged closure for said compartment, and means for bracing said closure when in open position to form a back rest for the device.

115 3. A device of the character described comprising an ornamental front portion, a rear portion, a hinged plate centrally of said rear portion, and adapted to be moved outwardly away from said rear portion, a loop on said rear portion for suspending the device, said loop being pivotally attached to said rear portion thereby to be movable upwardly and downwardly in a vertical plane, and a cup-shaped member on said plate adapted to receive said loop when moved downwardly and when the plate is swung outwardly away from said rear portion to thereby form a back rest for the device.

120 4. A device of the character described comprising an ornamental front portion, a rear

portion, a compartment in said rear portion adapted to retain a booklet, a hinged cover plate for said compartment, suspending means pivotally supported on said rear portion, and means on said cover plate cooperating with said suspending means when the cover plate is in open position for bracing said cover plate to thereby form a back rest for the device.

10 5. A device of the character described comprising an ornamental front portion, a rear portion, a compartment in said rear portion adapted to retain a booklet, a hinged cover plate for said compartment, a loop pivotally supported on said rear portion for suspending the device, and a cup-shaped member on said cover plate adapted to receive said loop when the cover plate is in open position.

6. A device of the character described comprising an ornamental front portion, a rear portion having a compartment, a hinged cover plate for said compartment forming a back rest for the device when in open position, a booklet suspended from near the top of said compartment and independently of said cover plate, and a leaf or button pivoted on said rear portion adjacent said plate for retaining the same in closed position and for retaining the booklet within the compartment when the plate is in open position.

7. A device of the character described comprising an ornamental front portion, a rear portion having a compartment, a booklet suspended in said compartment, a hinged cover plate for said compartment, means for bracing said cover plate when in open position to form a back rest for the device, and a leaf or button pivoted on said rear portion adjacent said plate for retaining the same in closed position and for retaining the booklet within the compartment when the plate is in open position.

8. A device of the character described comprising an ornamental front portion, a rear portion, a compartment in said rear portion, a booklet suspended in said compartment, a hinged cover plate for said compartment, suspending means pivotally supported on said rear portion, means on said cover plate cooperating with said suspending means when the cover plate is in open position for bracing said cover plate to thereby form a back rest for the device, and a leaf or button pivoted on said rear portion adjacent said plate for retaining the same in closed position and for retaining the booklet within the compartment when the plate is in open position.

9. A device of the character described comprising an ornamental front portion, a rear portion, a compartment in said rear portion, a booklet suspended in said compartment, a hinged cover plate for said compartment, a loop pivotally supported on said rear portion for suspending the device, a cup-shaped member on said cover plate adapted to receive said

loop when the cover plate is in open position, and a leaf or button pivoted on said rear portion adjacent said plate for retaining the same in closed position and for retaining the booklet within the compartment when the plate is in open position.

10. A device of the character described comprising an ornamental front portion, a rear portion of sheet material, the central portion of said sheet material being bent inwardly toward said front portion to thereby form a compartment adapted to contain a booklet, and a hinged closure for said compartment in alignment with the edges of said rear portion when in closed position.
